INTERMITTENT SCRAP CUTTER

Edgar R. Miller, Chicago, Ill., assignor to F. J. Littell Machine Company, Chicago, Ill., a corporation of Illinois

Application December 21, 1940, Serial No. 371,087

18 Claims. (Cl. 164—10.6)

The invention relates to improvements in scrap cutters of the type generally associated with punch presses and has more particular application to an intermittent scrap cutter having novel mechanism for actuating the same and which is adjustable for cutting the material into the lengths desired.

An object of the invention is to provide a scrap cutter of the vertical reciprocating type for association with punch presses and the like, which will be actuated from the press and in timed relation with the operations of said press, and which will embody novel means for predetermining the actuations thereof.

A more specific object is to provide a scrap cutter having intermittent operation in accordance with a master ratchet wheel which is rotated one notch for each punching cycle of the press. In accordance with the invention provision is made whereby the ratchet wheel may be changed to one having a different number of teeth since this will change the interval between actuations and will accordingly change the length of the scrap cut by the device.

Another object is to provide a reciprocating type of scrap cutter having an oscillating fulcrum member and wherein the parts are constructed and arranged to effect a cutting operation by changing the fulcrum point of said member.

A further object resides in the provision of an intermittent scrap cutter for association with punch presses and the like having electric means which will be rendered responsive at intervals measured by a predetermined number of strokes of the press for effecting actuation of the cutter.

With these and various other objects in view, the invention may consist of certain novel features of construction and operation, as will be more fully described and particularly pointed out in the specification, drawings and claims appended hereto.

In the drawings which illustrate an embodiment of the device, and wherein like reference characters are used to designate like parts—

Figure 1 is an elevational view looking toward the side of a press having the scrap cutter of the invention in associated relation therewith;

Figure 2 is a front elevational view of the scrap cutter showing the fulcrum member and the various parts connecting therewith;

Figure 3 is a front elevational view similar to Figure 2 but showing parts of the reciprocating cutter in vertical section and in the act of performing a cutting operation;

Figure 4 is a top plan view of the cutting mechanism proper showing the main fulcrum for the oscillating member and the latching means having association with the end thereof;

Figure 5 is a detail sectional view taken sub-

stantially along line 5—5 of Figure 1 and looking in the direction of the arrows;

Figure 6 is a detail sectional view taken substantially along line 6—6 of Figure 1; and

Figure 7 is a fragmentary view in elevation showing a modified form of ratchet wheel having a larger number of teeth and which may be substituted for that shown in the assembly of Figure 1.

Referring to the drawings, particularly Figure 1, the scrap cutter of the invention is shown in associated relation with a punch press or the like having a main operating shaft indicated by numeral 10 which is rotated at intervals to effect the punching operations. Said shaft also drives the scrap cutter and the timing mechanism which predetermines the actuation of said cutter, the same being measured in accordance with the invention by the strokes of the press. The eccentric 11 on the main operating shaft 10 of the press has connection at 12 with a connecting link 14 which is joined at its lower end as at 15 to a clevis 16. The clevis in turn has a releasable connection with an oscillating member 18. The pivot pin 20 joins the clevis 16 to the member 18 but this pin is removable in order that the point of connection may be varied as the openings 21 and 22 may also be utilized for this purpose. Except when the cutter is operative the oscillating member 18 has pivotal movement about a fulcrum point located substantially centrally thereof. This central fulcrum of the oscillating member is best shown in Figure 4, the same including a main fulcrum pin 23 which passes through the oscillating member 18 to extend a short distance beyond each of the hubs 24 formed integral with and on opposite sides of the member. These extending ends of the fulcrum pin 23 are journaled by the bifurcated extensions 25 projecting upwardly from the reciprocating cutter slide indicated in its entirety by numeral 26.

The slide shown in section in Figure 3 is formed along respective sides thereof with tubular portions 27 and 28 by means of which the slide is mounted for reciprocating movement in a vertical direction. The base 29, which provides the support 30 for the scrap material 31 to be cut by the reciprocating slide, has suitably fixed thereto a pair of spaced upright posts 33 and 34, the post 33 extending through the tubular portion 27, whereas, post 34 extends through tubular portion 28. Each tubular portion has secured thereto by screws 35 a member of substantially U-shape which may be considered as providing a spaced cap for its respective portion. The member 37 of U-shape is associated with tubular portion 27 and the member 38 of similar shape is associated with portion 28. Each member 35 positions a coil spring 40 between the same and

the post associated with its respective tubular portion. For example, as shown in Figure 2, the coil spring 40 is held in position within its member 37 by the bolt 41 which is actually a continuation of the post 33, since the bolt is threaded to the upper end of the post and is additionally secured thereto by the nut 42. Accordingly, the coil spring 40 is confined between the central portion of member 37 and the post 33, the same having contact with nut 42 which in turn rests on the post. The coil spring 40, located within member 38, is also associated with bolt 41 which provides a continuation of the post 34, see Figure 3. The cutter slide 26 is accordingly mounted on posts 33 and 34 for vertical movement, which movement is influenced by the tension exerted by the coil springs 40, the coil springs yieldingly maintaining the slide in elevated position wherein the U-shaped members 37 and 38 will engage the nuts 43 on the bolts 41. It will be clearly understood that the nuts 43 provide a stop limiting further movement of the cutter slide in an up direction under the tension exerted by the coil spring.

Except when the free end of the oscillating member 18 is held by structure to be described, the member fulcrums on the cutter slide 26. This takes place for a number of strokes of the press until a cutting operation on the scrap material is desired. By novel mechanism of the invention the free end of member 18 is latched with the result that the oscillating movement of member 18 will be imparted to the slide 26 to cause the slide to reciprocate on posts 33 and 34, which reciprocation in a downward direction is against the tension of coil springs 40.

As shown in Figures 2 and 3, the left hand end of the oscillating member 18 is provided with a pin 45 which projects from the respective sides of the member and these projecting ends are each located within a vertical elongated slot 46 formed in the side walls of a support 47. When the member 18 has pivotal movement about the fulcrum pin 23, it will be observed that this left hand end of the member will have free up and down movement within the support 47, the only association between this end of member 18 and the support being provided by pin 45 which rides within the slots 46. The support 47 is suitably secured to an adjustable post 48 projecting from the trunnion member 50. The post 48 is adjustable in order that the support 47 may be elevated or lowered to properly accommodate the end of the fulcrum member 18. Trunnion 50 is suitably journaled by the pivot pin 51 to spaced uprights 52 provided by the base 29. The latch 53 is pivoted to support 47 at 54 and movement of the latch is controlled by electric means in the form of a solenoid 55 having an armature 56 depending within the same, which armature is pivotally connected at 57 to the latch. As best illustrated in Figure 2, the latch is maintained in released position by the coil spring 58 carried by the rod 59 and which is confined on said rod and between the support and an adjustable nut 60. The end of rod 59 passing through the support is pivotally connected at 61 to the latch and since this connection is above the pivot 54 the latch is yieldingly urged in a clockwise direction which functions to maintain the depending ear or gag 62 in a position where the same is withdrawn and out of contact with the recessed end 63 of the oscillating member. It is possible for the

gag 62 to enter the recess on the end 63 of the oscillating member only when said end of the member has been depressed, which will be clearly evident from Figure 3. On the next stroke of the press oscillation of member 18 will take place with pin 45 as the fulcrum, and accordingly, movement will be imparted in a downward direction to the cutter slide.

As previously described, the solenoid 55 provides electrical means for controlling actuation of the latch 53 and in accordance with the invention said solenoid is energized at intervals measured by the strokes of the press. In other words, a predetermined number of strokes of the press will take place before the latch is actuated and following energization thereof the same number of strokes will again take place before the cycle is repeated. The solenoid is electrically connected by the conductor wires 64 with the switch box 65 which receives electrical energy from any suitable source by the conductors 66. The conductor wires 67 electrically connect the solenoid to a micro-switch 68 having an outwardly projecting switch contact member 70. The micro-switch 68 is suitably supported by the bracket 71 from the side wall 72 of the frame of the press and from said bracket there projects a stud having formed on its inner end the nut 73. Referring to Figure 6, the stud provides a bearing portion 74 for the oscillating arm 75 and a second bearing portion 76 of reduced diameter which rotatably mounts a ratchet wheel 77. The friction washers 78 produce a limited braking action on the ratchet wheel since the said wheel is resiliently held in contact therewith by the face washer 79 which is backed by the coil spring 80.

The arm 75 carries a pawl 81 which is pivoted to the arm by means of the bolt 82. Above the pawl at its extreme upper end arm 75 is pivotally secured at 83 to the connecting rod 84 which in turn is pivoted to the connecting link 14 at 85. It will be understood that when the main operating shaft 10 of the press rotates the eccentric will have up and down movement, which movement is imparted through connecting link 14 to the oscillating member 18, causing said member to oscillate and said eccentric will also have lateral movement. The corresponding lateral movement of the connecting link 14 is transmitted to the connecting rod 84 and as a result arm 75 is rocked and similar movement is imparted to pawl 81. The extent of movement of arm 75 is sufficient to cause the pawl to index the ratchet wheel one notch. In accordance with the invention the ratchet wheel 77 is provided with an even number of notches, as for example, forty-eight, which is divisible by such even numbers as 24, 12, 8, 6 and 2. An opening 86 is formed in the ratchet wheel 77 at the base of each notch and said openings are designed to receive a small bolt 87 having a rounded head which is positioned for contact with the switch contact member 70 of the micro-switch. If it is desired to effect a cutting operation for each twenty-four strokes of the press it will be understood that only two of the bolts 87 will be inserted in the ratchet wheel, these being placed at diametrically opposite positions. However, if a cutting operation is desired for every twelve strokes of the press four of the bolts 87 are used and these are located at ninety degree positions, as shown in Figure 1. Since the number of teeth on the ratchet wheel 77 is divisible by the small num-

bers as 8, 6, 4 and 2, it is possible to add additional bolts so as to effect a cutting stroke for operations of the press equivalent to these numbers.

The ratchet wheel 77 can be removed so as to permit another ratchet wheel to be substituted therefor, the operation requiring removal of the nut 88, coil spring 80, and the face washer 79. A ratchet wheel 90, such as shown in Figure 7, may be substituted therefor which is characterized by a larger number of teeth although each tooth has an opening 86 in alignment with the base thereof. Ratchet wheel 90 may have sixty teeth and by inserting the bolts 87 in various openings said ratchet wheel will function to energize solenoid 55 and effect a cutting operation for every two strokes of the press, for every three strokes, or for every six, ten, twelve, fifteen or thirty strokes. In fact, if only one of the bolts 87 is inserted in the ratchet wheel 90 a cutting stroke will take place for every sixty strokes of the press and with respect to ratchet wheel 77 for every forty-eight strokes of the press. It will be understood that other ratchet wheels may be substituted for the two herein shown and described, it being understood that the purpose of each wheel is to control the oscillating member 18 to effect a cutting operation at intervals measured by a predetermined number of strokes of the press.

Referring again to the cutter slide 26, the cutting mechanism may comprise any conventional structure such as shown in Figure 3. The plate 91 is suitably secured to the cutter slide and the same therefore forms the movable cutting blade which has movement with respect to the stationary blade 92 to cut the scrap material 31. In actual practice there is a tendency for the scrap material 31 to travel upwardly as the cutter slide moves upwardly. This may be prevented by a pressure and stripper plate 93 carried by the rod 94 supported for vertical movement by the bosses 95 projecting from and formed integral with the cutter slide. The collar 96 secured to the upper end of the rod 94 limits movement of the pressure and stripper plate 93 in a downward direction since movement in this direction takes place as a result of the tension exerted by the coil spring 97. It will be observed that the pressure and stripper plate is angularly positioned on rod 94 so as to present an open mouth for receiving the scrap material and to present a heel portion for positively engaging and holding the material adjacent the cutting blades 91 and 92. When the cutting operation has been completed and the cutter slide moves upwardly the plate 93 will maintain its position in engagement with the scrap material on support 30 and accordingly it functions to strip the material with respect to the cutter slide. Its additional function as a pressure plate will also be evident from the foregoing.

The electrical connection between the micro-switch 68 and the solenoid 55 results in energizing the solenoid each time the contact member 10 is actuated. Energization of the solenoid draws its armature 56 down and the latch 53 is accordingly caused to engage the recessed end 63 of the oscillating lever 18. On the next stroke of the press the fulcrumming point of said oscillating member will be shifted from the fulcrum pin 23 to the pin 45. Instead of member 18 fulcrumming about pin 23 bodily movement is imparted to said pin to cause reciprocating movement of the cutter slide 26. A cutting operation

on the scrap material accordingly takes place. As a result of this stroke of the press the ratchet wheel was indexed another notch and said indexing movement operates to free the switch actuating member 10 of the micro-switch so that the solenoid 55 is no longer energized. Therefore, at the end of this stroke of the press the latch 43 will be returned to initial position and the gag 62 will move out of contact with the recessed end of the oscillating member. On further strokes of the press the oscillating member 18 will fulcrum about its fulcrum pin 23 as before and this will continue until the above cycle is repeated by the next actuation of switch member 15 10 to again energize the solenoid.

What is claimed is:

1. In apparatus of the character described, a cutting slide mounted for substantially vertical reciprocating movement, an oscillating member having pivotal connection intermediate its ends with the cutting slide and which thereby provides a fulcrum for the member permitting pivotal movement in a substantially vertical plane, resilient means maintaining the cutting slide in an elevated position, means connecting with one end of said member for oscillating the same, and a latch in associated relation with the other end of said oscillating member, said latch in operative position pivotally holding said end to thereby shift the fulcrum point of the member whereby the member when oscillated imparts reciprocating movement to the cutting slide.

2. In apparatus of the character described, a cutting slide mounted for substantially vertical reciprocating movement, an oscillating member having connection with means at one end thereof for moving the same in a substantially vertical plane, means pivotally connecting the oscillating member approximately centrally thereof with the cutting slide and which thereby provides a fulcrum for the member, resilient means maintaining the cutting slide in an elevated position in contact with stop members, and a latch in associated relation with the free end of said member, said latch having an operative and inoperative position with said end, and when in operative position pivotally holding said end to thereby shift the fulcrum point of the member whereby the member when oscillated will impart reciprocating movement to the cutting slide.

3. In apparatus of the character described, a cutting slide mounted for substantially vertical reciprocating movement, an oscillating member having connection with means at one end thereof for moving the same in a substantially vertical plane, means pivotally connecting the oscillating member approximately centrally thereof with the cutting slide and which thereby provides a fulcrum for the member, resilient means maintaining the cutting slide in an elevated position in contact with stop members, a latch in associated relation with the other end of said oscillating member and normally assuming a released position with said end, whereby said oscillating member will normally fulcrum on the cutting slide, and means for actuating the latch into engaged position with said end of the member to pivotally hold said end in a down position, whereby the latch functions to shift the fulcrum point of the member so that the member when oscillated will impart reciprocating movement to the cutting slide.

4. In apparatus of the character described, a cutting slide mounted for reciprocating movement, an oscillating member having pivotal con-

nection intermediate its ends with the cutting slide to thereby provide a fulcrum for the member, resilient means maintaining the cutting slide in an elevated position in contact with stop members, means connecting with one end of said member for oscillating the same, a latch in associated relation with the other end of said oscillating member and in operative position pivotally holding said end to thereby shift the fulcrum point of the member, whereby the member when oscillated will impart reciprocating movement to the cutting slide, and electrical means for actuating said latch to an operative position.

5. In apparatus of the character described, a cutting slide mounted for reciprocating movement, an oscillating member having pivotal connection intermediate its ends with the cutting slide to thereby provide a fulcrum for the member, resilient means maintaining the cutting slide in an elevated position in contact with stop members, means connecting with one end of said member for oscillating the same, a latch in associated relation with the other end of said oscillating member and in operative position pivotally holding said end to thereby shift the fulcrum point of the member, whereby the member when oscillated will impart reciprocating movement to the cutting slide, resilient means maintaining said latch in an inoperative position, and a solenoid providing an armature having connection with the latch for actuating the latch to an operative position when energized.

6. In apparatus of the character described, the combination with a punch press having an operating shaft, of an oscillating member connecting with said shaft and which is oscillated during rotation thereof, a cutting slide mounted for vertical reciprocating movement, resilient means maintaining the cutting slide in an elevated position, means connecting the oscillating member intermediate its ends with the cutting slide to thereby provide a fulcrum for the member, and a latch having an operative and inoperative position with the free end of said oscillating member, said latch in operative position pivotally holding the free end of the member in down position to thereby shift the fulcrum point of said member, whereby said member when oscillated will impart reciprocating movement to the cutting slide.

7. In apparatus of the character described, the combination with a punch press having an operating shaft, of an oscillating member connecting with said shaft and which is oscillated during rotation thereof, a cutting slide mounted for vertical reciprocating movement, resilient means maintaining the cutting slide in an elevated position, means connecting the oscillating member intermediate its ends with the cutting slide to thereby provide a fulcrum for the member, a latch in associated relation with the free end of said oscillating member and which in operative position pivotally holds said end to shift the fulcrum point of the member, whereby the member when oscillated will impart reciprocating movement to the cutting slide, and means for actuating the latch to an operative position.

8. In apparatus of the character described, the combination with a punch press having an operating shaft, of an oscillating member connecting with said shaft and which is oscillated during rotation thereof, a cutting slide mounted for vertical reciprocating movement, resilient means maintaining the cutting slide in an elevated position, means connecting the oscillating member intermediate its ends with the cutting slide to

thereby provide a fulcrum for the member, a latch in associated relation with the free end of said oscillating member and in operative position pivotally holding said end down to thereby shift the fulcrum point of the member, whereby the member when oscillated will impart reciprocating movement to the cutting slide, resilient means maintaining said latch in a released position with respect to the free end of the member, and electrical means for actuating the latch to an operative position.

9. In apparatus of the character described, the combination with a punch press having an operating shaft, of an oscillating member connecting with said shaft and which is oscillated during rotation thereof, a cutting slide mounted for vertical reciprocating movement, resilient means maintaining the cutting slide in an elevated position, means connecting the oscillating member intermediate its ends with the cutting slide to thereby provide a fulcrum for the member, a latch in associated relation with the free end of said oscillating member and in operative position pivotally holding said end down to thereby shift the fulcrum point of the member, whereby the member when oscillated will impart reciprocating movement to the cutting slide, resilient means maintaining said latch in a released position with respect to the free end of the member, and a solenoid providing an armature for connecting with the latch for actuating the latch to an operative position when energized.

10. In a scrap cutter for association with a punch press, in combination, a base providing spaced upright posts and mounting between the posts a stationary cutting blade, a reciprocating slide supported by said upright posts and providing a movable cutting blade for coaction with said stationary blade, resilient means maintaining the cutting slide in an elevated position against stop means, a member having pivotal connection intermediate its ends with the cutting slide to thereby provide a fulcrum for the member permitting oscillating movement thereof, means connecting with one end of the member for oscillating the same, a latch in associated relation with the other end of the member and having an engaged and a released position therewith, said latch when engaged pivotally holding its end of the oscillating member in a down position to thereby shift the fulcrum point of the member, whereby the member when oscillated will impart reciprocating movement to the cutting slide.

11. In a scrap cutter for association with a punch press, in combination, a base providing spaced upright posts and mounting between the posts a stationary cutting blade, a reciprocating slide supported by said upright posts and providing a movable cutting blade for coaction with said stationary blade, resilient means maintaining the cutting slide in an elevated position against stop means, a member having pivotal connection intermediate its ends with the cutting slide to thereby provide a fulcrum for the member permitting oscillating movement thereof, means receiving actuation in timed relation with the press and connecting with one end of said member for oscillating the same, a latch in associated relation with the other end of said member and having an engaged and a released position therewith, said latch when engaged pivotally holding its end of the oscillating member in a down position to thereby shift the fulcrum point of the member, whereby the member when oscillated will impart reciprocating movement to the

cutting slide, and electrical means for actuating the member into an engaged position.

12. In a scrap cutter for association with a punch press, in combination, a base providing spaced upright posts and mounting between the posts a stationary cutting blade, a reciprocating slide supported by said upright posts and providing a movable cutting blade for coaction with said stationary blade, resilient means maintaining the cutting slide in an elevated position against stop means, a member having pivotal connection intermediate its ends with the cutting slide to thereby provide a fulcrum for the member permitting oscillating movement thereof, means receiving actuation in timed relation with the press and connecting with one end of said member for oscillating the same, a latch in associated relation with the other end of said member and having an engaged and a released position therewith, said latch when engaged pivotally holding its end of the oscillating member in a down position to thereby shift the fulcrum point of the member, whereby the member when oscillated will impart reciprocating movement to the cutting slide, resilient means maintaining the latch in a released position, and a solenoid providing an armature having connection with the latch for actuating the latch into an engaged position when energized.

13. In a scrap cutter for association with a punch press, in combination, a cutting slide mounted for vertical reciprocating movement, an oscillating member having movement in timed relation with operations of the press, means pivotally connecting the member approximately centrally thereof with the cutting slide which thereby provides a fulcrum for the member, resilient means maintaining the cutting slide in an elevated position against stop members, a latch having associated relation with the free end of said oscillating member and in engaged position pivotally holding said end to shift the fulcrum point of the member, whereby the member when oscillated will impart reciprocating movement to the cutting slide, a rotatable ratchet wheel having contact members located in predetermined spaced relation around the periphery thereof for electrically actuating the latch to an engaged position, and means indexing the ratchet wheel one notch for each operation of the press.

14. In a scrap cutter for association with a punch press, in combination, a cutting slide mounted for vertical reciprocating movement and yieldingly held in an elevated position, an oscillating member fulcrummed on said cutting slide at approximately the mid-point of said member, means connecting with one end of the member for oscillating the same in timed relation with the operations of the press, a latch having an engaged and a released position with the other end of the member, said latch in engaged position pivotally holding said end of the member to shift the fulcrum point, whereby the member upon oscillating movement will impart reciprocating movement to the cutting blade, resilient means maintaining the latch in a released position, a solenoid providing an armature having connection with the latch for actuating the latch into an engaged position when energized, and means for periodically energizing said solenoid including a rotatable member, an electric switch for said solenoid, and switch contact means lo-

cated in spaced relation around the periphery of said rotatable member.

15. In a scrap cutter for association with a punch press, in combination, a cutting slide mounted for vertical reciprocating movement and yieldingly held in an elevated position, an oscillating member fulcrummed on said cutting slide at approximately the mid-point of said member, means connecting with one end of the member for oscillating the same in timed relation with the operations of the press, a latch having an engaged and a released position with the other end of the member, said latch in engaged position pivotally holding said end of the member to shift the fulcrum point, whereby the member upon oscillating movement will impart reciprocating movement to the cutting blade, resilient means maintaining the latch in a released position, a solenoid providing an armature having connection with the latch for actuating the latch into an engaged position when energized, and means energizing the solenoid at intervals measured by the operations of the press including a rotatable ratchet wheel having switch contact means located in spaced relation around the periphery thereof, a switch electrically connecting with the solenoid and located for actuation by said contact means, and other means indexing the ratchet wheel one notch for each operation of the press.

16. In a scrap cutter for association with a punch press, in combination, a reciprocating cutting slide, an oscillating member for actuating said slide, said member having movement during each operation of the press, a latch for rendering said member effective to actuate the cutting slide to perform a cutting operation, electro-magnetic means for operating said latch, a ratchet wheel having switch contact means located in predetermined spaced relation around the periphery thereof, a switch member electrically connecting with the electro-magnetic means and positioned for actuation by said contact means, and other means indexing the ratchet wheel one notch for each actuation of the press.

17. In a scrap cutter for association with a punch press, in combination, a reciprocating cutting slide, an oscillating member for actuating said slide, said member having movement during each operation of the press, a latch for rendering said member effective to actuate the cutting slide to perform a cutting operation, electro-magnetic means for operating said latch, and a rotatable ratchet wheel having indexing movement for each operation of the press and controlling the electric circuit to said electro-magnetic means.

18. In a scrap cutter for association with a punch press, in combination, a reciprocating cutting slide, an oscillating member for actuating said slide, said member having movement during each operation of the press, a latch for rendering said member effective to actuate the cutting slide to perform a cutting operation, electro-magnetic means for operating said latch, and means for energizing said electro-magnetic means at predetermined intervals measured by the operations of the press to thereby render said latch operative to cause a cutting operation.
